UNITED STATES PATENT OFFICE

ALBERTUS COENRAADES KORSTEN AND MACHIEL DE VISSER, OF ROTTERDAM,
NETHERLANDS

ADJUSTABLE SPRING-MOUNTED CHAIR

Application filed March 7, 1929, Serial No. 345,066, and in the Netherlands March 17, 1928.

The invention relates to an adjustable, spring-mounted chair, e. g. an office-chair, the seat of which being revolving, adjustable in various heights and at the same time 5 spring-mounted.

The drawback of such chairs is, that the chair should be calculated for persons of different weight, while notwithstanding this the construction should be simple. 10 The chair according to the invention is arranged so that two springs are mounted in order to support the seat resiliently, which springs are put into action in succession, while one of them serves at the same time as 15 a screw-worm for the height-adjustment of the chair, under the application of a clutch, mounted between said spring and the spindle of the seat, which clutch in released condition enables the seat to turn, without altering 20 the height-adjustment of the chair.

The advantage of this is, that a simple and solid construction is obtained, whereas the person sitting on the chair, may turn without the height-adjustment of the chair altering. 25

The drawing illustrates by way of example the under-frame of the chair according to the invention, partly in section.

Preferably the construction is entirely made up of metal, in consequence of which 30 the chair may be made in mass. The under-frame of the chair according to the invention comprises a number, e. g. three legs 1 of tube metal, interconnected by e. g. two supporting yokes 2, 3, likewise made of tube metal.

35 The seat of the chair (which has not been drawn) is arranged on a rod 4 having a reduced end 5. On the place in which the diameter of the rod is reduced, there is an abutment 6 supporting the coiled spring 7 arranged round the end 5 of the rod, which 40 coiled spring rests with its lower side on a bottom 8 of a bush 9, enclosing the rod 5 and the spring 7.

The said bush 9 rests normally with its 45 upper part against a ring 10 of the yoke 2, through which ring the rod 4 passes. The lower end of the bush 9 is mounted freely movably in an opening 11 of a ring 12 of the lower yoke 3. In some places near the upper 50 edge of the bush 9, this bush is incised ver-

tically so that in those places a lip 13 is formed, which is bent outwardly and thereupon somewhat shortened in case of need. The lips 13 are arranged so that they are disposed in the screw-worms of a strong spring 55 14. The upper end of the spring 14 rests in its released condition against the ring 10 and is bent downwardly behind the cam 13, so that this bent end 15 comes to rest on the second convolution of the spring 14 and the 60 cam 13 can never slip out of the spring.

The lower end of the spring 14 is bent at 16 and rests in an opening 17 of the ring 12.

The bottom portion 8 is provided with a 65 cavity 18 in which a pin 19 may rest, which pin is inserted fittingly in an opening of the rod 5.

The device according to the invention works as follows: 70

In case one wishes to adjust the chair according to the invention in the desired height, the seat is revolved in the same manner as a music stool, without taking seat on the chair. Thereby the rod 4 revolves and the pin 19 of the end 5 laying in the cavity 18, takes along with it the bottom portion 8 and at the same time the bush 9. Consequently the cams 13 between the convolution of the spring 14, which in that case act as 80 screw-worms, are screwed downward so that the seat of the chair, together with the members connected to it, sinks, since the bush 9 is adapted to sink freely through the opening 11 of the ring 12. 85

As soon as the seat has substantially arrived at the desired height whereby the springs remain absolutely unstrained, one may take place on the chair. Hereby first of all the spring 7 is compressed. By this 90 the pin 19 gets off the cavity 18 so that the seat may revolve in every direction without changing thereby the adjusted height of the chair, since the rod may rotate freely in the bush 9.

A further advantage of this construction is that the chair is calculated for the most varying weights of the persons using the chair.

With lighter persons only the weaker 100

spring 7 is compressed. With heavier persons the stronger spring 14 will be compressed after the spring 7 having been compressed to a certain degree.

5 In this manner a supple springing chair is constructed in a simple way, which chair is suited for every weight and the seat of which may be revolved in all directions without altering anyhow the height-adjustment of the chair.

10 Moreover the construction according to the invention is cheap and easily to be made in mass, whereas its duration of life is very long.

15 We claim:

1. A device of the class described comprising upper and lower rings, a seat supporting rod slidably associated with the rings and having an abutment, a bushing surrounding the rod and having a bottom slidably receiving the rod, a coiled spring surrounding the bushing, a lip carried by the bushing and engaged between the helices of the spring, a coiled spring in the bushing surrounding the rod and having its upper and lower ends engaging, respectively, the abutment and bushing bottom, said spring being of less strength than the first named spring, and a clutch connection between the rod and said bottom.

2. A device of the class described comprising upper and lower rings, a seat supporting rod slidably and rotatably associated with the rings, a bushing surrounding the rod and slidable in the lower ring, a spring encircling the bushing, means for interlocking the spring and the lower ring, a lip carried by the bushing and engaged between the helices of said spring, a bottom for the bushing, said bottom having a cavity therein, a pin carried by the rod, said pin when engaged in the cavity serving to interlock the bottom and rod to impart rotary movement to the bushing when the rod is rotated, and to permit free rotation of the rod upon disengagement of the pin from the cavity.

In testimony whereof we affix our signatures.
